UNITED STATES PATENT OFFICE.

SIDNEY WORMS, OF NEW ROCHELLE, NEW YORK, ASSIGNOR TO FRANKLIN KNITTING MILLS, INC., OF NEW YORK, N. Y., A CORPORATION OF NEW YORK.

DESIGN FOR A GRENADE LACE STRIPE FABRIC.

Application filed May 5, 1923. Serial No. 6,077. Term of patent 3½ years.

To all whom it may concern:

Be it known that I, SIDNEY WORMS, a citizen of the United States of America, and a resident of the city of New Rochelle, Westchester County, New York, have invented a new, original, and ornamental Design for Grenadine Lace Stripe Fabric, of which the following description, in connection with the accompanying drawing, is a specification.

The single figure of the drawing is a plan view of the grenadine lace stripe fabric showing my new design.

I claim as my invention:

The ornamental design for a grenadine lace stripe fabric as shown.

SIDNEY WORMS.
